UNITED STATES PATENT OFFICE

132,974

DESIGN FOR AN ASH TRAY

Charles F. Hines, Clarksburg, W. Va.

Application May 25, 1942, Serial No. 106,996

Term of patent 14 years

To all whom it may concern:

Be it known that I, Charles F. Hines, a citizen of the United States, residing at Clarksburg, in the county of Harrison and State of West Virginia, have invented a new, original, and ornamental Design for Ash Trays, of which the following is a specification, reference being had to the accompanying drawing, forming part thereof, and in which

Fig. 1 is a top plan view of an ash tray showing my new design;

Fig. 2 is a side elevational view thereof;
Fig. 3 is a bottom plan view thereof; and
Fig. 4 is a detail perspective view of one of the rests.

I claim:

The ornamental design for an ash tray, as shown.

CHARLES F. HINES.
